UNITED STATES PATENT OFFICE.

MAX A. SKALL, OF NEW YORK, N. Y., ASSIGNOR OF ONE-HALF TO
EDWIN B. HIRSCH, OF BROOKLYN, NEW YORK.

SHOW-CASE.

No. 820,828.

Specification of Letters Patent.

Patented May 15, 1906.

Application filed January 6, 1906. Serial No. 294,841.

To all whom it may concern:

Be it known that I, MAX A. SKALL, a citizen of the United States, residing in New York, in the borough of Manhattan, county 5 and State of New York, have invented certain new and useful Improvements in Show-Cases, of which the following is a specification.

This invention relates to certain improvements in show-cases, and more especially to 10 show-cases of that class which are known as "frameless" show-cases, in which the edges of the glass plates forming the top, front, and side walls of the show-case are held in direct abutment by suitable fastening means, so as 15 to present a glass edge instead of a wooden or metal edge.

In the frameless show-cases at present in use the glass plates forming the side and top walls of the show-case are usually connected 20 by suitable fasteners attached to the plates by rivets passed through holes drilled in the plates. The boring of these holes has to be accomplished by means of diamond drills, and hence it is slow and costs considerable.

25 The object of this invention is to avoid this drilling of the plates forming the walls of the case and to connect said plates in a reliable manner without any drilling of holes; and for this purpose the invention consists in 30 the novel features of construction, which will be fully described hereinafter and finally pointed out in the claims.

In the accompanying drawings, Figure 1 is 35 a perspective view of my improved show-case. Fig. 2 is a vertical section on line 2 2, Fig. 1. Fig. 3 is a top view of Fig. 1. Fig. 4 is a horizontal section on line 4 4, Fig. 2. Fig. 5 is a bottom view, drawn on a larger scale, of the top corner-pieces of the show-case and 40 its connections. Fig. 6 is a perspective view of one of the front corner-plates, showing the means for attaching the connecting-rods thereto. Fig. 7 is a detail perspective view of one of the connecting parts shown in Fig. 45 6, and Fig. 8 is a detail perspective view of another such part.

Similar letters of reference indicate corresponding parts in the different figures of the drawings.

50 Referring to the drawings, *a* represents the bottom of my improved show-case, which bottom is provided with soft-rubber studs *a'* for resting on the floor at some distance from

the same. In place of the rubber studs any other support for the bottom *a* may be used. 55 The frame is provided with a front and side molding *a*² and at the back with an upright frame *b*, which is closed by a hinged door *b'*. The front and the side walls *d* *d'* of the frame are formed of glass plates, the said glass 60 plates abutting against the front glass plate, said plates being made of suitable thickness and the side plates abutting against the molding of the bottom *a* and against a raised ledge of the rear frame *b*. The top glass 65 plate *d*² rests on the upper edge of the front and side plates *d* *d'* and on the top of the rear frame *b*. The corners of the front, side, and top plates are connected by front and rear corner-pieces *e* *e'*, of which the front corner-pieces *e* are connected with the base-frame 70 by means of vertical screw-rods *f*, that pass through the bottom of the bottom frame *a* and are firmly held in position by screw-nuts *f'*, that are screwed on the lower threaded 75 ends of the connecting screw-rods. The front corner-pieces *e* are connected with each other by a horizontal front rod *g*.

Each end of the rod *g* is threaded into one 80 end of a tubular angle-piece *e*³, (shown in Figs. 6 and 8,) and said angle-piece is soldered to the under portion of a triangular plate *e*⁴, which is spaced downwardly from the under surface of the corner-piece *e* by its upwardly-disposed side flanges *e*⁵ and which 85 is in turn soldered to said corner-piece. For the purpose of increasing the strength of the solder-joint between the angle-piece and the plate *e*⁴ the latter is provided with openings *o*, as shown in Fig. 7, in which the solder 90 hardens, thereby firmly locking said angle-piece to said plate. In the rearwardly-extending leg of each angle-piece *e*³ is threaded a connecting-rod *g'*, by means of which the corner-pieces *e* are connected with their corresponding rear corner-pieces *e'*, said rods being soldered to the under surface of said last-named pieces, as shown in Fig. 5. The intermediate or apex portions of the angle-pieces *e*³ and triangular spacing-plates *e*⁴ are 95 provided with cut-away portions *e*⁶ *e*⁷, respectively, through which the vertical rods *f* pass, as shown in Fig. 6, and in which they are soldered. By this arrangement the angle-pieces *e*³ are spaced inwardly from the 100 downwardly-extending flanges of the corner 105

pieces, so as to receive the side glass plates d' between the same, and spaced downwardly from the under surfaces of said corner-pieces in order that the connecting-rods g g' may support the top plate d^2 , which is disposed between said rods and said corner-pieces, being cut away at its corners, as shown in Fig. 5.

In case horizontal glass shelves h are used they are supported on brackets f^2 , which are soldered to the vertical screw-rods f and to screw-eyes f^3 or other supports applied to the rear frame b .

When the top corner-pieces are applied to the front, side, and top glass plates and to the rear frame b and the screw-nuts f' applied to the lower ends of the vertical screw-rods f , the plates are tightly connected with the rear frame and a strong frameless show-case obtained, which can be shipped in detached state and readily assembled and put up for use. The hinged rear door is provided with suitable locks, so as to give access to the show-case to the parties whose goods are exhibited in the same. In place of hinged doors sliding doors or any other arrangement of doors giving convenient access to the

goods exhibited on the shelves may be arranged.

Having thus described my invention, I claim as new and desire to secure by Letters Patent—

In a show-case, the combination, with a base and back frame, of front, side, and top glass plates, rear corner-pieces applied to the upper corners of said back frame, front corner-pieces resting on the upper surface of the top plate and having depending flanges abutting against the side plates and front plate, and connecting-rods spaced inwardly from the flanges of said corner-pieces and between which and said flanges the side plates and front plate are disposed, certain of said rods connecting the front corner-pieces with the rear corner-pieces, while another such rod connects the front corner-pieces.

In testimony that I claim the foregoing as my invention I have signed my name in presence of two subscribing witnesses:

MAX A. SKALL.
